TAPE RECORDER DECK

Robert C. Henderlong and Larry W. Smith, Tulsa, Okla.,
assignors to Midwestern Instruments, Inc., Tulsa, Okla.,
a corporation of Oklahoma

Filed Jan. 27, 1964, Ser. No. 78,370

Term of patent 14 years

(Cl. D26—14)

Fig. 2.

Fig. 1.

FIG. 1 is a front elevational view of a tape recorder deck showing our new design; and

FIG. 2 is an end, elevational view.

The dominant features of the design reside in the portions shown in full lines.

We claim:

The ornamental design for a tape recorder deck, as shown and described.
